PORTABLE SITZ BATH

Cecil D. Gaston and William D. Moore, Birmingham, Ala.

Application November 2, 1937, Serial No. 172,422

10 Claims.

(Cl. 4-6)

This invention relates to sitz baths and among other objects, aims to provide an improved portable sitz bath which has unusual features of construction contributing to the safety and comfort of the patient and the convenience of the hospital staff employing the bath. Other objects of the invention will be apparent from the following description of a preferred embodiment thereof.

10 In the drawings,—

Fig. 1 is a perspective view;

Fig. 2 is a bottom plan view; with a portion broken away, showing in dotted lines another position of the foot rests;

15 Fig. 3 is a vertical section on line 3—3 of Fig. 2;

Fig. 4 is a rear end elevation; and

Fig. 5 is an enlarged vertical section on line 5—5 of Fig. 3.

Referring particularly to the drawings, the improved sitz bath comprises a base 10 which is preferably made of enameled cast iron or of some highly polished metal whose surface is easily kept clean and sanitary. The base 10 is adapted to support the basin or tub 11 in which the patient sits, and is in turn supported by casters 12, 13, preferably three in number, two of the casters 12 being at the forward end of the base and the third caster 13 being swivelled at the rear end of the same, as best shown in Fig. 3.

30 Preferably all three casters have rubber tires or treads, as indicated, so that they may be rolled noiselessly over hospital floors and corridors. At its rear end the base 10 is formed with a vertical socket 14 which receives the swivel pin 15 of the

35 caster 13. Centrally the base 10, which is crowned or elevated relative to its edge, as shown, is provided with an aperture 16 bordered by an integral down-turned flange 17. The basin or tub sits directly over the aperture 16 and has a pair of perforated ears 18 through which hook bolts 19 are passed, said hook bolts having special washers 20 formed with grooves 21 for receiving the edge of the down-turned flange 17. Ordinarily nuts 22 are threaded on bolts 19

40 and bear against the special washers 20 and thus tighten the special washers against the edge of flange 17 and secure the basin 11 on base 10 by means of ears 18. Instead of this construction, the base 10 may be integral with the basin, as 45 will be understood without illustration. The basin 11 is provided with a drain outlet 23 which may be plugged with a rubber stopper (not shown) when water is to be placed in the basin for a bath.

50 To provide a convenient member which may

be grasped by the patient when getting into and out of the tub, a frame is provided consisting of a generally U-shaped pipe or tube 24, said tube surrounding the basin on three sides and lying generally horizontal and being shaped to conform to the curvature of the rearwardly inclined back rest 11^a of the tub. Studs or rivets 24^a may secure the U-shaped tube 24 to ears 24^b depending from the rim of the tub. At its forward ends, the U-shaped tube 24 is secured by pipe fittings 5 25 to a pair of upright tubes 26 comprising standards. Obviously the tubing 24, 26 may be chromium plated or otherwise made ornamental, to improve the appearance of the bath. The upper ends of the standards 26 are capped with ornamental knobs 27 which, besides enhancing the appearance of the sitz bath, serve the useful function of providing hand grips which the patient may grasp when lowering himself into the tub and when rising out of the same.

20 The lower ends of the standards 26 are secured to the forward arms 10^a of the base 10, said arms being formed by providing the forward end of said base with a re-entrant portion or recess indicated at 10^b. This re-entrant portion is very 25 desirable because it permits the patient closely to approach the basin or tub before he sits in it and eliminates all sense of fear when using the bath. Instead of the tub and frame connections, described above, another upright tube 30 30 might be joined by a T to tube 24 at the middle of its curved rear portion, and also might be connected to the tub base above roller 13 in the same manner as the standards 26.

35 As best shown in Figs. 1 and 2, the standards 26 provide swivel supports for a pair of foot rests 28 which are adapted to swing freely horizontally about the axes of standards 26 between the positions shown in full lines in Fig. 2 and the 40 positions indicated in dotted lines. The foot rests each have outer flanges 28^a against which the sides of the patient's feet may press, so that he will not lose his footing. A pair of lugs 29 formed on collars 30 which are integral with the casting 16 serve as stops to prevent outward 45 swinging of the foot rests 28, which would be very undesirable as the foot rests would undoubtedly strike against various articles if they were allowed to project laterally beyond the 50 confines of the bath. Instead of a swivel mounting for the foot rests, they may be hinged by conventional hinges (not shown) to the standards 26. As the patient takes his place in the 55 bath his feet will readily locate the foot rests

and he will then be able to swing them into the positions most conducive to comfort.

When the patient gets in or out of the bath, a pedal-operated brake 31, operating on the axle 5 32 of the rear caster 13 by means of the cam action of screw thread 33 and the disk 34 (Fig. 5) obviates movement of said caster, and because of the friction of the rubber treads of the casters prevents any movement of the bath, thus obviating accidents.

The described sitz bath is strictly sanitary, is easily moved in and out of the patient's room, and permits the patient, while standing on the floor, to sit down in a perfectly natural way and 15 be comfortable in the tub before removing his feet from the floor. This is a great advantage when a patient uses the bath, as ordinarily most patients using the crude equipment formerly available lose their sense of balance and confidence. Furthermore, the bath is so designed that it may be drained easily. Ordinarily most of the bath water is siphoned off, but some must be drained, and cleansing fluids must be drained too. At such times a pan (not shown) is inserted 25 from the front, under the raised edge 10^c, which may be as much as eight inches off the floor, making possible the use of a pan of adequate capacity.

Obviously the present invention may be embodied in several forms neither described nor shown.

Having described and shown one embodiment of our invention, what we claim as new and desire to secure by Letters Patent is:—

35 1. A portable sitz bath comprising a wheeled support having an aperture in its upper, central portion; a tub or basin of proper shape and size to receive the buttocks and thighs of a patient and removably mounted on the support above the aperture; means adjacent the edges of said aperture to clamp the tub to the support; a framework secured to and extending above the support and surrounding said tub so as to provide 40 convenient hand holds and arm rests for the patient.

50 2. The invention according to claim 1, wherein the framework comprises two vertical standards secured to one end of the support, and a U-shaped tube embracing and directly attached to the rim of the tub and secured at its ends to the two standards.

55 3. In a sitz bath, the combination of a base having a re-entrant portion at one end; a pair of foot rests at said end mounted to swing horizontally, said foot rests being above the bottom of the base and at either side of the re-entrant portion; and a tub or basin clamped on the base and removable therefrom, said tub or basin having substantially its entire body back of the re-60 entrant portion of the base.

4. In a portable sitz bath, the combination of a base; a tub or basin on the base; two casters beneath the forward end of the base, and a single caster swivelled on the rear end of the base;

and a brake on the rear, swivelled caster to secure it against rotation, thereby to prevent travel of the bath.

5. A sitz bath comprising, in combination, a base; a tub or basin set on top of the base and secured thereto; and a frame secured to the base comprising a pair of standards and a U-shaped member secured at its ends to the standards and lying substantially at right angles to the standards; said tub or basin being secured at at least 10 two points to the U-shaped member, which is wholly outside of the tub or basin; said standards being at one end of the base and being spaced well apart.

6. The invention according to claim 5, where- 15 in there are a pair of foot rests swivelled on the standards at their lower ends, and means are provided to limit the outward swing of said foot rests.

7. In combination with a base having a re- 20 entrant portion at the front end forming two integral arms at either side of the re-entrant portion, a tub on top of and clamped to the base; a pair of foot rests pivoted above the ends of said arms to swing horizontally into and out 25 of the re-entrant portion; and hand holds on either side of the tub, supported from the base.

8. The invention according to claim 4 where- 30 in the base has a re-entrant portion at the front end forming two integral arms at either side of the re-entrant portion; and two casters being located directly beneath the outer ends of the arms and the third caster being swiveled to the base at the opposite or rear end and at a point within the medial axis of the base.

35 9. In combination with a base having a re-entrant portion at the front end, and two arms at either side of the re-entrant portion; a pair of fixed vertical standards rising from the outer ends of the arms; a horizontal U-shaped mem- 40 ber secured to the standards near their upper ends and lying to the rear of the standards; and a tub set on said base and secured thereto; said U-shaped member embracing the tub; said re-entrant portion extending sufficiently far inwardly to bring it beneath the forward portion of the tub, to facilitate entering the tub from the floor on which the base rests.

45 10. In a sitz bath, the combination of a tub or basin having a drain outlet, and a base to which the tub is removably clamped; said base being crowned so that the major portion is much higher than its edge, thereby affording room beneath the base for a vessel to receive the drainage of the tub; the forward end of the base 50 having its edge raised so that such a vessel may be slid in under said raised edge; said base also having a re-entrant portion at its forward end, said re-entrant portion extending sufficiently far inwardly to bring it beneath the forward portion 55 of the tub.
